UNITED STATES PATENT OFFICE.

SAMUEL MORRIS LILLIE, OF PHILADELPHIA, PENNSYLVANIA.

MANUFACTURE OF SALT BY MULTIPLE-EFFECT EVAPORATION.

1,086,457.

Specification of Letters Patent. Patented Feb. 10, 1914.

Application filed March 15, 1910. Serial No. 549,541.

To all whom it may concern:

Be it known that I, SAMUEL MORRIS LILLIE, a citizen of the United States, residing at Philadelphia, in the county of Philadelphia and State of Pennsylvania, have invented a new and useful Improvement in the Manufacture of Salt by Multiple-Effect Evaporation.

The purpose of my invention is to adapt, for the purpose of manufacturing salt from brine, my vapor or heat reversing multiple effect which is described in United States Letters Patent #777,114, issued December 13th, 1904, and which is shown in various modified constructions in my United States Patents #789,159, May 9th, 1905, #939,143, November 2nd, 1909, #984,376, February 8th, 1910. The construction of this multiple effect is such that it may be operated with either end effect of the series as the hottest effect and either end effect the coolest effect. When one end effect is the hottest one, the other end effect is the coolest one of the series, and vice versa. The object of this adaptation is to take advantage of the changes in temperature caused in the various effects of the multiple effect by the reversing of the direction of the vapors to prevent the formation of incrustations upon the evaporating surfaces during the evaporation of the brine.

My invention consists in combining with effects of the vapor reversing multiple effect, separating devices by which the salt crystals formed in the several effects by the evaporation of the brine may be separated from the brine and delivered away from the multiple effect.

An arrangement of apparatus embodying my invention is illustrated in the accompanying drawings of which

Figure 1 is an elevation, Fig. 2 is a plan view. Fig. 3 is a cross section of each of the cocks mentioned.

Referring to the figures in which like parts are indicated by like letters or numbers, A, B and C are the three evaporator effects of a Lillie-vapor reversing multiple effect, each of which is constructed in a general way as indicated in my Letters Patent referred to in the preceding and also in earlier Letters Patent granted to me, that is, each effect is horizontal, is divided into two chambers by a vertical partition, which also

serves as a tube plate, near one end of the 55 effect. This partition or tube plate is indicated in the plan Fig. 2 by the dotted lines at 'e' in the case of each effect. The smaller of these chambers is designated the "steam end" and the larger the "vapor 60 end." Horizontal evaporating tubes located in the vapor end open through this tube plate into the steam end. The ends of the tubes in the vapor end are closed save for a small air vent and extend only part way 65 through the vapor end chamber. The heating agent steam or vapor is led into the "steam end" chamber, whence it flows into the evaporating tubes and causes evaporation from the liquid in contact with the tubes in 70 the "vapor end" chamber, which is provided with a vapor escape main. In the elevation, Fig. 1, the effect B is shown in vertical section taken across the broken line X—X Fig. 2. The section discloses to view the closed 75 ends of the evaporating tubes in effect B and a perforated distributing plate above the tubes. The effects are turned end for end so that the steam end of each effect is in line with the vapor end of each adjacent effect. 80 In the drawings the respective ends of each effect are indicated by the designations "Steam end" and "Vapor end." The vapor end of each effect is connected with the steam end of each adjacent effect by a vapor 85 main fitted with a valve. The middle effect B is connected with the steam end of effect A by a vapor main 4 fitted with a valve 8 and it is connected with the steam end of the effect C by a vapor main 7 90 equipped with the valve 9. The vapor end of effect A is connected with the steam end of effect B by the main 5 fitted with the valve 10 and the vapor end of effect C is connected with the steam end of effect B by 95 the vapor main 6 fitted with the valve 11. The vapor end of the effect A connects by the vapor main 12 with the condenser 13, having the leg pipe L, and the vapor end of the effect C connects by the vapor main 14 with the condenser 13, having the leg pipe L'. The condensers 13 and 15 are 100 ejector condensers in which the cooling water serves to maintain the vacuum as well as to condense the vapors. Condenser 13 is 105 supplied with water through the pipe 16 fitted with a valve 17 and condenser 15 is supplied with water through pipe 18 fitted

with a valve 19. Although not shown, a steam supply pipe fitted with valve leads into the steam end of effect A at N, and a similar steam pipe leads into the steam end 5 of effect C at N'—see Fig. 2.

On the under side of each effect is a well W which opens below into a centrifugal circulating pump 1. The three pumps are shown on a common shaft 2, which is 10 revolved by a motor M or by other suitable means. Between the effects A and B is the settler S.

Between the effects B and C is the settler S' both of the same construction. Each 15 settler is an inverted four-sided pyramid with sides parallel and perpendicular to the length of the triple effect. In Fig. 2 the top plate or cover of settler S' is removed. In Fig. 1 interior construction of 20 the settler S' is indicated by dotted lines which show a narrow passage O and O' inside the settler and on opposite sides of the same. These passages O and O' are closed below and open above near the top of the 25 settler. The passage O has an inlet nozzle with which connects the pipe 23. The passage O' has a discharge nozzle with which connects the pipe 36. The settler S has inside passages similar to O—O' of settler S', 30 and with them connect pipes 25 and 40.

S' is a settler open at the top, and of the general shape of an inverted truncated four-sided pyramid. On one side or face of this 35 settler and covering the upper portion of it is the thin inlet passage O³ which opens above into the settler near the top and into which below opens the inlet pipe 27. The settler S' serves as a boot for the bucket elevator E. In front of this elevator in the 40 settler S' is the partition p which forms in the settler in front of the elevator a buffer like compartment. A pipe 20 communicates with a discharge nozzle on each of the three 45 circulating pumps 1 by a connection 21. Through the three way cock 22 it communicates with the pipe 23 leading into settler S' at the side, which pipe 23, may, by the 50 said cock and pipe 20, be connected with the pump 1 of either B or C. Pipe 20 also communicates through the three way cock 24 with the pipe 25 which leads into settler S at the side, which pipe 25 can be connected to the pump 1 of either effect A or B through the cock 24 and pipe 20. The pipe 55 27 leading into the passage O³ on settler S' connects through the three-way cock 26 either with the pipe 20 or with the pipe 28. Connecting also with a discharge nozzle from each of the centrifugal pumps 1 is a 60 pipe 29, which connects through the three way cock 30 with the pipe 31 which leads into the settler S' a short distance above its lower end or apex. The pipe 29 through the three way cock 32 connects with the pipe 33 which leads into the side of the settler 65

S a short way above its lower end or apex. Pipe 34 is a drain pipe with valve connections 35 to a discharge from each circulating pump. From the side of the settler S' opposite to the pipe 23 a pipe 36 leads up to the three way cock 37 through which it communicates either with the pipe 38 delivering upon the distributing plate in the body C or with the pipe 39² which delivers upon the distributing plate in body B. From the side of the settler S opposite to the pipe 23 a pipe 40 leads to the three way cock 41 by which it can communicate either with the pipe 39² delivering upon the distributing plate in the effect B or with the pipe 42 which delivers upon the distributing plate in effect A. From inside the settler S' back of partition p a pipe 43 leads to the three way cock 44 through which it may communicate either with the pipe 42 which delivers upon the distributing plate in the effect A, or with the pipe 45 which connects with the pipe 38, and through it delivers upon the distributing plate in the effect C. Pipe 43 is fitted with the balanced valve V which is operated by the connected float F. The settler S at its bottom or apex is connected to the three way cock 39, through which it may communicate through the connecting pipe 40² with the well W 95 of effect B, or through the connecting pipe 41² with the well W of effect A. The settler S' connects at its bottom or apex with the three way cock 46 through which it may communicate, by the connecting pipe 43 with the well W of effect B, or by the connecting pipe 44 with the well W of the effect C. The valved pipe f leading into the well W of effect A is the fresh brine feed to that effect, the valved pipe f' is a fresh brine 100 feed to effect C and the valved pipe F² is a fresh brine feed into the open settler S'. By Fig. 3 is indicated the construction of any one of the three way cocks herein mentioned.

The operation of the described combination of parts is as follows, viz: First, let it be assumed that the apparatus is charged with brine and is operating with A the hottest effect and C the coolest effect. Steam is 110 entering the steam end of A at N, and steam to C at N' is shut off. Water is passing through the pipe 18 into the condenser 13 of effect C and water is shut off from condenser 13 of effect A. The vapor valves 10 and 9 are open, the vapor valves 8 and 11 are closed, and the course of the heat or vapors through the series is as indicated by the single barbed arrows—see Fig. 2. The effects are each charged with brine up to the 115 desired points as indicated by gage glasses, one of which is indicated in Fig. 1 at g on effect B. The settlers S, S' are full of brine and the settler S' is also full of brine to 120 about the height indicated in Fig. 1. The 125

elevator E and the circulating pumps 1 are running and the fresh brine is feeding into effect A through the feed pipe f as controlled by the hand valve in the latter. The three way cocks are set so that movements of the brine are as follows: The brine is circulating from the bottom of effect A through its circulating pump 1, and pipes 20 and 25 into the side of the settler S, across near the top of the settler, down on the other side and by the pipes 40 and 42 through the top of effect A upon its perforated distributing plate by which the brine is distributed over the battery of evaporating tubes below, as indicated at effect B, Fig. 1. The salt crystals which are formed in the brine in A by its evaporation, pass with the circulating brine into the settler S, and settle away from the brine as it flows across near the top of the settler and falls down toward and to the bottom or apex of the settler due to the salt crystals having a greater specific gravity than the brine. Brine is circulating from effect B through the pipes 20 and 23 into the side of settler S' up and across the same near the top, down the other side of the settler and by the pipes 36 and 39² through the top of effect B upon its distributing plate. A portion of brine from effect B is forced by its circulating pump 1 through the pipe 29, cock 32 and pipe 33 into the settler S a little above its apex and passes back into the well W of effect B through the cock 39 and pipe 40². This brine which circulates from the bottom of effect B through the lower part of settler S, back into the effect B carries with it into the effect B the salt which comes into the settler S, from effect A. The brine which circulates, as above described, from the bottom of effect B through the settler S', carries with it and deposits in the settler S', this salt which comes forward from the settler S into B, and also the salt crystals which are formed by the evaporation of brine in B. Hence the salt crystals formed by evaporation in effects A and B are deposited in settler S'. Brine is circulating from the bottom of effect C through its circulating pump 1 through the pipe 28, cock 26 and pipe 27 into the passage O³ on the side of settler S², thence across the top of the brine in the settler over the partition p and back through the pipe 43, cock 44, and pipes 45 and 38 into effect C through the top. The flow back through the pipe 43, etc., is automatically regulated by the balanced valve V and its float F to compensate for the flow of brine into the settler from the effect C through the pipes 28 and 27 and so maintain the level of the brine in S² constant within certain limits: A portion of brine circulates from effect C through the pipe 29, cock 30 and pipe 31, into the settler S' a little above its bottom or apex and through the cock 46 at

its apex and pipe 44 back into the effect C through its well W. This circulation of brine from the effect C through the settler S' back into the effect C, brings into the latter the salt crystals which deposit in the settler, that is the salt crystals formed by evaporation in effects A and B. These salt crystals together with those formed by evaporation in effect C, that is the crystals formed by evaporation in all three effects, are carried by the brine circulating from the effect C through the open settler S² into the latter, in which they fall from the brine as it flows across the surface of the brine in the settler and settle to the bottom and are taken away by the bucket elevator E.

The regulation of the brine levels in the effects A, B, and C is done as follows: The hand valve in the brine feed pipe f to the effect A, the hottest effect, is regulated to maintain the desired level of brine in effect A. The three way cocks 32 and 39 are regulated so that the flow from the bottom of settler S through pipe 40² into the effect B is in excess of the flow from effect B through pipes 29 and 33 into the settler S: this excess is really a feed or flow of brine from the effect A through the settler S into effect B. This "feed" can be regulated in amount by either the cock 32 or the cock 39, the other cock being set only part way open, to maintain the desired level of brine in effect B, and is so done. The three way cocks 30 and 46 are regulated so that the flow of brine from the bottom of settler S' into the effect C through the pipe 44 is in excess of the flow from the effect C through the pipes 29 and 31 into the settler. This excess is a feed of brine from the effect B through the settler S' into the effect C: this feed is regulated in amount to maintain the desired level of brine in effect C, either by the cock 30 or by the cock 46, the other cock being set only part way open. It may be noted here that their levers are so set up on the cocks that they all point or incline toward the coolest effect and it will be observed from what follows that if the levers of all the cocks be turned to the opposite side of the nearest vertical radius, the cocks will all be set for working with C the hottest effect and A the coolest effect and will all point or incline toward A, the coolest effect.

The apparatus may be changed from operating as above, viz. with A the hottest effect and C the coolest effect, to operating with C the hottest effect and A the coolest as follows: Shut off steam from effect A at N, close valve in brine feed pipe f to effect A, and close cocks 30, 32, 39 and 46 by turning their levers into the nearest vertical position. All flow or feed of brine is now stopped into A and from A to B and from B to C, but the circulation of brine is still in force through each effect and its connect-

ed settler. Preferably after the pressure (or vacuums) in the three effects are nearly equalized, shut water off the condenser 15 by the valve 19 in the water line 18, and turn 5 water into the condenser 13 by opening the valve 17 in the water line 16. Close now the cocks 22, 24 and 26 by moving their levers into the nearest vertical position. Turn the inclined levers of the cocks 41 and 37 and 44 10 to the inclination on the other side of the nearest vertical position and then further move the levers of the cocks 22, 24 and 26 to incline to the vertical from the sides opposite to what they were when working with A the 15 hottest effect. Open the valve 8 in vapor main 4 and valve 11 in vapor main 6, and close the valves 10 and 9 in the vapor mains 5 and 7 respectively. Now turn steam into 20 effect C at N' and open the valve in the brine feed f' line to effect C and regulate to maintain the desired brine level in C. Open the cocks 30 and 46 part way by turning their levers toward effect A and regulate the feed from C to B by one of the cocks to 25 maintain the desired level of brine in effect B, and open the cocks 32 and 39 part way by turning their levers toward effect A, and by one or the other cocks regulate the flow or 30 feed of brine from effect B into effect A to maintain the desired brine level in A. The triple effect is now operating with C the hottest effect and A the coolest effect. Brine is 35 circulating from the bottom of effect C through the settler S' and back into C through the top, depositing in the settler the salt crystals formed by evaporation in C. Brine is circulating from the bottom of effect B through the settler S back into B at the top depositing in the settler the salt crystals 40 formed in effects C and B, and brine is circulating from the bottom of effect A through the open settler S² and back into A through the top, depositing the salt crystals formed 45 in the three effects in the settler S² from which it is taken away by the bucket elevator E. The salt crystals are moved from the settler S', now serving for effect C, into effect B by the brine circulating from the bottom of effect B through the lower part 50 of settler S' as led by the pipes 29, 31 and 43 and cocks 30 and 46, and the salt crystals are moved from the settler S, now serving for effect B, into effect A, by the brine circulating from the bottom of effect A through the pipes 29, 33 and 41² and the cocks 32 and 39. The levers of all the cocks of the apparatus 55 are now inclined toward the effect A (now the coolest), as indicated by the short dotted line at each cock, the brine and salt are moving from the effect C toward the effect A, and the vapors are doing the same, namely as per the double barbed arrows on the vapor mains 6 and 4. Reversing back to 60 work with A the hottest effect and C the

coolest effect is done in a manner similar to the reversing just described. Steam is changed from effect C to effect A, the water is changed from condenser 13 to condenser 15 and the cocks are manipulated as described only the levers are moved in the opposite direction which brings them back into the positions shown in Fig. 1. It is to be observed that each settler serves one or the other of the adjacent effects depending upon whether A is the hottest effect or the coolest effect. Effects A and C are considered "adjacent" to the open settler S². 70

In the foregoing descriptions, the feed of brine is into the hottest effect, and down from body to effect to the coolest through the intermediate settlers. The brine, however, may be made to flow in the opposite direction, viz., into the coolest effect and from effect to effect to the hottest effect; for example, if when A is the hottest effect the feed of fresh brine be taken into the coolest effect C, as regulated by the valve in the feed pipe f' , the brine may be caused to flow into the effect B from C by regulating the cocks 30 and 46 so that the flow into the 80 settler S' from C, through the pipes 29 and 31 shall be in excess of the flow from the settler back into C by the pipe 44; this excess or feed finds its way into the effect B from the settler with the circulating liquor 85 through the pipes 36 and 39² and the cock 37, and its quantity may be regulated to maintain a desired level of brine in effect B by one of the cocks 30 and 46. In a similar way brine may be made to feed from effect 90 B into A to maintain the desired level in A by manipulating the cocks 32 and 39. The circulating pumps exert sufficient pressure on the brine to move it forward in this manner from effect to effect against the increasing pressures which correspond to the increasing temperatures. 95

The brine in the effects may be carried at different levels with the effect of obtaining different size salt crystals. If the brine level 100 be carried below the lower row of tubes, the crystals obtained will be the finest, for the brine is always in a high state of agitation due to its falling from tube to tube during all of its passage over the evaporating tubes 105 suffering evaporation. If the brine level be carried above the upper row of tubes, the brine, it is evident, will be in a comparatively low degree of agitation during the evaporation and the crystals formed will be 110 larger. With the brine carried at intermediate levels, the average of the grains produced will be of an intermediate size. 115

It is evident that there may be a greater number of effects in the series and a correspondingly greater number of settlers and have the connections between the parts and the operation similar to that herein de- 120 125

scribed for a series of three effects, and also that there may be other modifications without departing from my inventions. For example, the effects may be constructed with 5 the settling chambers directly beneath the heating surface, as indicated in the drawings of my application #575,371, filed August 3rd, 1910, and still meet the terms of my invention in a number of particulars.

10. Methods of working which are involved in the preceding description, as for example the varying of the size of the salt crystals by varying the levels at which the brine is carried in the effects, will be covered in other 15 applications for Letters Patent of the United States.

I claim as of my invention—

1. The combination with the effects of multiple effect evaporator of two or more 20 effects arranged with respect to its steam and vapor connections so that it may be operated with either end effect the hottest effect, the combination with the effects of a settler for each pair of adjacent effects with 25 pipe connections between the settler and each of the effects of the pair to connect it with either effect of the pair as desired in a circulation relation and means for circulating the brine, from the effect through the 30 settler with which it is connected and back into the body again substantially as described.

2. In the combination with the effects of a vapor reversing multiple effect with a settler for each pair of adjacent effects, pipe 35 connections from each effect to the portion of the settler in which the separated crystals deposit and back to the effect and means for circulating the brine from the effect 40 through the settler and back to the effect to move the deposited crystals from the settler into the effect substantially as described.

3. A multiple effect evaporator for the manufacture of salt from brine by evaporation, in which salt crystals are formed in the brine in two or more of the effects, a device 45 for separating salt crystals from brine, means for causing a flow of brine through a suitable conduit into the said device sufficiently rapid to move salt crystals through the conduit into the said device, and means 50 for delivering the salt crystals formed in the two or more effects into the said conduit and into the brine flowing through the conduit to the said device for separating salt crystals from brine.

4. A multiple effect evaporator for the manufacture of salt from brine by evaporation, in which salt crystals are formed in the 55 brine in two or more of the effects, a device for separating salt crystals from brine, means for causing a flow of brine through a suitable conduit into the said device sufficiently rapid to move salt crystals through

the conduit into the said device and means 65 for delivering the salt crystals formed in the two or more effects into the said conduit and into the brine flowing through the conduit to the said device for separating salt crystals from brine and means for delivering back 70 into the multiple effect the brine after the salt crystals have been separated from it.

5. A vapor reversing multiple effect evaporator for the manufacture of salt from brine by evaporation in which the steam and 75 vapor connections are such as to permit of either end effect serving as the hottest effect, and the other end effect as the coolest effect, means for taking away salt formed in either end effect in a current of brine to a device 80 for separating salt from brine, and means for delivering salt formed in other effects of the multiple effect into the same current of brine.

6. In a vapor reversing multiple effect 85 for the manufacture of salt from brine by evaporation, means for reversing the direction of the vapors and heat through the effects as a series, and means for reversing the direction of the movement of the salt 90 formed in the several effects along the series of effects to correspond with the said direction of the vapors and heat.

7. A multiple effect evaporator for making salt from brines by evaporation, in 95 which salt crystals are formed in the brine in two or more of the effects; means for collecting the salt crystals formed in these effects into one of the effects of the multiple effect, a device for separating salt crystals 100 from brine, and means for delivering salt crystals suspended in a current of brine from the said one effect into the said device for separating salt crystals from brine.

8. A multiple effect evaporator for making salt from brines by evaporation, in which salt crystals are formed in the brine in two or more of the effects; means for collecting the salt crystals formed in these effects into one of the effects of the multiple 110 effect, a device for separating salt crystals from brine, and means for delivering salt crystals suspended in a current of brine from the said one effect into the said device for separating salt crystals from brine, and 115 means for delivering the brine separated from the salt back into the multiple effect.

9. A multiple effect evaporator for the manufacture of salt from brines by evaporation, in which the salt crystals are formed 120 in two or more of the effects; means for collecting salt formed in the several effects into one effect and means for taking the salt away from the said one effect and thereby away from the multiple effect.

10. A multiple effect evaporator for the manufacture of salt by the evaporation of brine in which salt forms in the several

effects; means for delivering salt from each of the hotter effects into the coolest effect, and means for taking the salt away from the coolest effect, and thereby from the multiple effect.

11. A series of evaporators for the manufacture of salt from brine by evaporation, in which series salt is formed in each of the evaporators, a collecting evaporator for the salt from all the evaporators of the series; means for delivering the salt formed in each evaporator through all the evaporators in succession between it and the collecting evaporator and then into the collecting evaporator and means for removing the salt from the collecting evaporator and thereby from the series of evaporators.

12. An evaporator for making salt from brines by evaporation, having a salt settling space into which the salt settles away from the evaporating brine, a brine holding tank, means for maintaining an adequate volume of brine in the tank, and means for delivering the salt from the salt settling space

of the evaporator suspended in a current 25 of brine into the said brine tank and permitting the salt to settle through the brine in the tank, and means for delivering brine back into the evaporator from the tank.

13. An evaporator for making salt from 30 brines by evaporation, having a salt settling space into which the salt settles away from the evaporating brine, a brine holding tank, means for maintaining an adequate volume 35 of brine in the tank, and means for delivering the salt from the salt settling space of the evaporator suspended in a current of brine into the said brine tank and permitting the salt to settle through the brine in the tank, and mechanism for removing 40 the settled salt from the brine tank.

In testimony whereof I have signed my name to this specification in the presence of two subscribing witnesses.

S. MORRIS LILLIE.
